UNITED STATES PATENT OFFICE.

LESLIE W. CLAYBOURN, OF MILWAUKEE, WISCONSIN.

MOLD-BEARER-CUTTING MACHINE.

Application filed May 16, 1927. Serial No. 191,915.

It is the object of my invention to provide means whereby to cut bearers in a mold for a printing plate, in order that the printing plate formed from such mold may be equalized throughout its area for resistance to pressure and bending forces applied to the printing plate. My invention is exemplified as operating upon a so-called wax mold, although it is obvious that the material of 10 which the mold is composed is not restrictive upon my invention.

It is a practice of the modern making of printing plates to exert pressure upon the printing plate while the printing surface 15 thereof is resisted by a smooth hard surface, in order to bring the various printing surfaces of the printing plate into the same plane, whether the plate be flat or curved, the plane in the instance of curved plates 20 being a cylindrical plane, and it is also the practice to bend a flat printing plate in order to form a curved printing plate suitable for instance for application to a plate cylinder of a rotary printing press.

Many printing plates are provided with printing portions in only a part or in separated parts of the area thereof, and many other printing plates are provided with printing portions which are more compact, 30 or in which the printing lines are broader, in some portions of the printing plate than in others, with the result, when pressure is applied to compress the printing plate, or to press all parts of its printing portions into 35 the same plane, that uneven resistances to the pressure forces are found in different parts of the printing plate, those parts with light, few or separated printing surfaces being obliged to resist the same pressures as 40 those parts with more condensed printing surfaces, or larger printing areas, in consequence of which the light or separated printing surfaces and the edges of printing areas are unduly pressed, and a printing plate is 45 produced which is not perfect.

It has also been found that upon bending stresses being applied to printing plates having unequal or unbalanced areas of printing portions, that unequal resistances to said 50 bending stresses are found in the various portions of the printing plate, depending on the unevenness of the distribution of the printing surfaces thereon, and a curved

printing plate is produced which is irregular in its curvature, or in the location of all its 55 printing surfaces in the same cylindrical plane.

The form from which a mold is made is usually composed of type, cuts and the like, or previously made printing plates, or any 60 one or more of these. The form is usually surrounded by a marginal line of bearers, these bearers being primarily for the purpose of preventing shifting of the form on the mold when pressure is applied between 65 the form and the mold, for causing indentations or depressions in the mold of the printing portions and the bearers.

It is the object of my invention to provide means whereby the mold, in which such depressions of printing portions are made, with additional or after-formed bearer depressions in the unprinting portions of the mold, so that, when the printing plate has 70 been formed from such mold, as by electro-depositing, casting or other process, or one or more of the same, there are printing areas 75 and bearer areas of equal height well distributed throughout the printing plate, for forming the printing plate at its various 80 portions of equal thickness in order to resist pressure, bending stress, or the like, to substantially equal extent throughout the area of the printing plate.

The printing depressions formed in molds 85 are in practice of different depths in different molds, depending on the solidity, openness or extent of the printing areas in the form, and the pressures applied in forming the mold therefrom. It is the object of my 90 invention further to provide novel means whereby to gage the depth of the cutter for forming the after-formed bearer depressions in the mold; further, to provide novel means for determining the cutting relation of the 95 cutting tool to the mold; further, to provide novel means for controlling the operative relation between the cutting tool and the mold; and, further, to provide novel means for providing coactive movements between 100 the cutting tool and the mold.

The invention will be further readily understood from the following description and claims, and from the drawings, in which latter:

Fig. 1 is a plan view of a mold having 105

therein areas of printing portions and areas of unprinting portions as heretofore usually constructed.

Fig. 2 is a cross-section of the same, taken 5 on the line 2—2 of Fig. 1.

Fig. 3 is a cross-section of the same, taken on the line 3—3 of Fig. 1.

Fig. 4 is a plan view of the same, showing the mold after being operated upon by my 10 improved device.

Fig. 5 is a cross-section of the same, taken on the line 5—5 of Fig. 4, showing the after-formed bearer-depressions in the mold.

Fig. 6 is a cross-section of the same, taken 15 on the line 6—6 of Fig. 4.

Fig. 7 is a plan view of a printing plate, which may be an electrotype, made from the mold shown in Figs. 1, 2 and 3.

Fig. 8 is a cross-section of the same, taken 20 on the line 8—8 of Fig. 7.

Fig. 9 is a cross-section of the same, taken on the line 9—9 of Fig. 7.

Fig. 10 is a plan view of a printing plate made from a mold shown in Figs. 4, 5 and 25 6, having my invention applied thereto.

Fig. 11 is a cross-section of the same, taken on the line 11—11 of Fig. 10.

Fig. 12 is a cross-section of the same, taken on the line 12—12 of Fig. 10.

Fig. 13 is an enlarged detail of the latter.

Fig. 14 is a front elevation of my improved device.

Fig. 15 is a side elevation of the same, partly broken away.

Fig. 16 is a fragmentary rear elevation 35 of the same.

Fig. 17 is a plan view of the same.

Fig. 18 is a vertical longitudinal section of the same, taken on the line 18—18 of Fig. 40 17, and partly broken away.

Fig. 19 is a fragmentary vertical cross-section of the same, taken on the line 19—19 of Fig. 17.

Fig. 20 is a cross-section of the same, taken 45 on the line 20—20 of Fig. 19.

Fig. 21 is a detail of the positioning means for the cutter, taken in section in the plane of the line 21—21 of Fig. 18.

Fig. 22 is a cross-section of the same, taken 50 in the plane of the line 22—22 of Fig. 18.

Fig. 23 is a detail of the stop for the cutter operating bar, taken in section on the line 23—23 of Fig. 16.

Fig. 24 is a side elevation of the cutter 55 in its socket, the latter shown in vertical section; and,

Fig. 25 is a cross-section of the same, taken on the line 25—25 of Fig. 24.

The printing plates may be electrotypes, 60 stereotypes, or printing plates otherwise formed, or formed of different material. The printing plate 31 is exemplified as an electrotype, (see Figs. 9 and 13), which comprises an electro-deposited shell 32 and a 65 backing 33 of metal cast in the shell.

In the modern practice of correcting printing plates it is usual to support the printing surface of the printing plate by a smooth hard surface and to apply pressure to the printing plate for bringing all the printing surfaces thereof into the same plane, as shown, described and claimed for instance in United States Letters Patent No. 1,549, 70 185, granted to me August 11, 1925, for improvements in method of correcting printing plates and printing plates produced thereby.

It has been found, in applying pressure upon a printing plate which has unbalanced areas of printing surface, that those portions 80 of the printing plate, as at 34, which have restricted or small areas of printing surface, and the edges 35 of printing portions of the printing plate adjoining unprinting portions, are less resistant to the pressures 85 applied to the printing plate, than the printing portions thereof, as at 36 (Fig. 7), which have greater areas of printing surface, with the result that such portions of less resistance are likely to be and often are deformed 90 or spread, in a manner to mar the excellence of the printing plate.

It has also been found, in curving printing plates thus formed with unbalanced printing areas, that the thicker portions of 95 the printing plate resist the bending stresses to greater extent than the thinner portions, resulting in a curved printing plate in which the printing surfaces are not in as true cylindrical form as they should be, or in which 100 the curvature of the printing plate is irregular.

In order to avoid these objections, I provide the unprinting portions of the printing plate, as at 37, (Figs. 7, 8 and 9), with 105 additional thickness so as to balance the resistances of the printing plate throughout its area. I accomplish this by providing the printing plate with additional bearers in the unprinting portions thereof, or in the 110 spaces adjacent to the printing portions, as exemplified by the raised portions or bearers 38 in the printing plate. (See Figs. 10, 11, 12 and 13.)

These bearers aid in resisting the pressure 115 applied to the printing plate in correcting the same, and aid in resisting the bending stresses when curving the printing plate, so that excess pressure is taken off of the isolated printing parts of the printing plate, and 120 crushing, deforming or mutilation thereof is avoided, and so that a uniform body for the printing plate is provided in which the resistance to bending stresses is substantially 125 evenly distributed for enabling a uniform curvature to be applied to the plate.

After the printing plate has been corrected, or curved, and otherwise completed, as the case may be, the extra bearers are removed by routing, or in other desirable man- 130

ner, for instance, to the dotted line 39 in Fig. 13, so that the unprinting portions of the printing plate are in properly low relation to the printing portions of the printing plate for proper inking and printing. The printing plate is formed from or upon a mold, which has in it the reverse counter parts of the printing plate formed thereby.

The mold may be of suitable character, but is instanced as a usual wax mold 42, comprising a layer or sheet of wax in which an impression of the printing form is made by pressure, this layer or sheet of wax being upon a backing sheet of metal. The mold, as thus made, referring to Figs. 1 to 3 inclusive, is instanced as embodying printing portions 44, 45, 46, and unprinting portions 47, corresponding to the printing portions 34, 35, 36, and the unprinting portions 37 in the printing plate and corresponding portions in the form from which the mold is made. This form is surrounded by a line of form bearers, the depressions of which are shown at 48 in the mold. These form bearers are at the outer margins of the form and are provided primarily for the purpose of preventing lateral shifting of the form on the mold when pressure is applied. The depths to which the printing portions of different forms are pressed into their respective molds vary.

Whenever printing portions, unprinting portions, and bearers or bearer portions of the mold are hereinafter mentioned, it will be understood that those portions of the mold are referred to from which the printing portions, the unprinting portions and the bearers or bearer portions respectively of the printing plate are formed, these respective portions in the mold being the reverse in elevation and direction of the corresponding portions in the printing plate formed therefrom.

When employing my improved device I first form the mold with the usual printing areas, and the usual unprinting areas, the latter being represented in the mold by the retained thickness of the material of the mold, or by leaving such portions of the mold unimpressed.

I provide the mold thus preformed, with after-formed bearer-depressions, which in the mold are represented by additional depressions 51, (see Figs. 4, 5 and 6), formed in the mold by removal of material therefrom to a depth equal to the depth of the impressions of the printing characters in the mold. These bearer-depressions may assume various shapes, and extend throughout different areas, depending on the arrangement and character of the printing surfaces which are formed in the mold by the printing form, the object being to associate such printing portions of the mold thus preformed with after-formed bearer-depressions of equal

depth adjacent thereto, so as to relieve slight or separated printing areas or characters in the printing plate formed from the mold of undue pressure, and to transfer the resistances to such pressure to the additional bearers thus formed in the printing plate as counterparts of the bearer-depressions thus formed in the mold.

It is desirable to form these bearer depressions in the mold by removal of materials from the face side of the mold, and it is desirable that this removal shall be accurately accomplished so as to provide bearer depressions which are equal in depth to the depth of the printing depressions. I prefer to accomplish this removal by means of a cutting edge of a cutting tool which is sunk into the unprinting portions of the mold to a depth equal to the depth of the depressions of the printing characters in said mold, and to cause travel between such cutting edge and the mold so as to form a groove or grooves in said unprinting portions of a depth equal to the depth of the printing depressions, the cutting tool removing the material of the groove or grooves past the surface of the face side of the mold.

This removal may be accomplished by a single passage between the tool and the mold, with the tool at extreme depth in the mold, namely in the plane of the bottoms of the printing depressions, or by a number of such passages to remove the material of the mold in successive steps in each of which the tool is deeper in the mold, until in the final passage the tool is in the plane of the bottoms of the printing depressions in the mold.

I prefer that the travel between the cutting edge and the mold shall be in various directions, depending on the shape of printing areas adjacent to the unprinting portions and the extent of such unprinting portions.

After the bearer depressions have been cut into a wax mold, any rough edges left by the cutting tool are smoothed or removed by the momentary application of a hot blast which melts such rough edges.

The apparatus exemplified comprises a bed 61, supported on a suitable base, shown comprising legs 62, rigidly secured to the base, and tied together by tie-rods.

A carriage 65 is slidable on guides 66 on the bed, the carriage being provided with guideways 67 complementary to the guides.

The mold 42 is arranged to be rigidly held to the carriage so as to lie flat on the plane supporting surface of the carriage, as by means of clamps 68. The carriage is provided with an undercut groove 69, in which a base 70 provided with tongues is arranged to slide. A clamping arm 71 is pivoted to the base by a pin 72 located in bearings of lugs in the base and in the arm. A screw-rod 73 is held downwardly by its head being

received in a recess 74 in the base. The screw-rod passes freely through a hole 75 in the clamping arm. A nut 76 is received over the threaded portion of the screw-rod 5 and has a handle 77 by means of which the nut may be readily turned for clamping the clamping shoe 78 of the clamping arm upon the mold, clamping the mold to the carriage. A spring 79 between said arm and said base 10 normally urges the clamping arm in unclamping direction.

A screw-rod 81 is journaled in bearings 82, 83, in the bed, and is held endwise therein by collars 84, 85, pinned to the screw-rod.

15 A hand-wheel 86 and handle 87 thereon are arranged to turn the screw-rod. A nut 88 depends from and is fixed to the carriage and is threaded to the screw-rod. Rotation of the screw-rod moves the carriage in one 20 direction or the other along the guides therefor on the bed according to the direction of rotation of the hand-wheel.

A cutter 91 having a cutting edge 92 is arranged to coact with the mold on the carriage. The cutter is releasably secured to a cutter-bar 93, as by insertion of its shank 94 in a socket 95 in said cutter-bar, and the clamping of said shank in said socket by means of a set-screw 96 having a turning 30 knob 97 thereon. Cutters having cutting edges of different widths or shapes are arranged to be interchanged in cutting position on the cutter-bar.

The cutting edge is adjustable toward and 35 from the supporting face of the mold for determining the depth of the cut to be made in the mold, and means are provided for moving said cutting edge toward and from the mold for moving the cutting edge into 40 and out of the face side of the mold, and means are provided for positioning the direction in which the cutting edge is presented for presenting the cutting edge in proper relation according to the direction of 45 movement between the cutting edge and the mold.

The cutter-bar is mounted in bearings 101, 102, on a slide 103. The cutter-bar is positioned endwise in said bearings, as by locating the bearings between a shoulder 104 on 50 said bar and a handle 105 fixed to the opposite end of said bar. The cutter-bar is rotatively positioned in said bearings, and is provided with recesses 106, which recesses 55 are shown 90° apart. A ball 107 in a socket 108 in the wall of the bearing 101 is normally urged toward said cutter-bar by a spring 109 in said socket. The ball is received in said respective recesses for maintaining the cutter-bar in adjusted position 60 during the cutting operation.

The slide 103 is mounted on a rocker-arm 111 and is adjustable to elevation thereon. A screw 112 is journaled and held endwise 65 in a bearing 113 on a bracket 114 on said

slide, and is threaded into a threaded hole 115 in said arm. The screw-rod is provided with a handle 116 for ready rotation of the same. Rotation of the screw adjusts the screw up or down, according to the direction 70 of rotation, for positioning the cutting edge. The slide is slidable in a guideway 117 in the arm. The slide is clamped to the arm after adjustment by means of a clamp-screw 121 extending through a slot 122 in 75 the slide and threaded into a threaded hole 123 in the arm. A washer 124 is received between the walls of said slot and a head 125 on said screw. A handle 126 is fixed to said head for manipulation of the screw.

80 The arm is pivoted to and adjustable lengthwise of a screw-rod 131 journaled in bearings 132, 133, upon brackets 134, 135, extending from the bed. The screw-rod is held endwise in said bearings by shoulders 136, 137, coacting with said bearings. A hand-wheel 138 having a handle 139 thereon is fixed to said screw-rod for rotating the same. When the screw-rod is rotated, the arm 111 is moved crosswise of the bed in one 90 direction or the other, depending on the direction of rotation of the screw-rod.

95 The rocking movement of the rocker-arm is obtained by a bar 141 received in a fork 142 in said rocker-arm. The respective ends of the bar are received in guideways 143 in the inner faces of brackets 144 extending from the brackets 134, 135. The rocker-arm moves lengthwise of said bar during the lateral travel of said rocker-arm. The faces of the bar coacting with the faces of the fork in said rocker-arm are preferably rounded, as shown at 145, for accurate movement of the rocker-arm and close engagement between the engaging surfaces of said bar and said fork throughout the lateral positions and rocking movements of the rocker-arm.

100 Stops 151 are provided at the respective ends of the bar. These stops are shown as 110 clips for closing the upper ends of the guideways 143, and are secured to the brackets 144 by bolts 152. These stops limit the extent of movement of the cutting edge into the mold, and, with the adjustment of the cutter slide, determine the depth of the cut 115 made by the cutting edge.

Movement of the cutting edge out of the mold is obtained by the retracting movement of a treadle 155, on a treadle-lever 156, 120 which is pivoted on a tie-rod 157 between the side frames of the base, and is articulated at 158 with a link 159. The link 159 has articulation at 160 with an arm 161 fixed to a rocker-rod 162 journaled in bearings 163 on brackets 164 extending from the brackets 134, 135.

125 Rocker-arms 165 are fixed to the respective ends of said rocker-rod and have articulations 166 with links 167 having articu- 130

lations 168 with the respective ends of the bar 141.

A spring 171, the respective ends of which are secured to the tie-rod 172 and to the 5 treadle-lever 156 normally holds the treadle-lever in raised relation, and urges movement of the bar 141 away from the stops 151. The cutting edge 92 is normally positioned at its limit of movement away from the bed.

10 If it is desired to operate on a mold, the mold is slipped under the cutter and clamped to the table. The cutter-support is adjusted laterally by rotation of the hand-wheel 138, and, if necessary, the carriage 15 is moved by rotation of the hand-wheel 86, to position the cutter at a printing depression in the mold, the cutter being out of contact with the mold. The cutting edge is caused to descend into said printing depression by depression of the treadle and the height of the cutting edge is adjusted by rotation of the hand-wheel 116, so that the cutting edge just touches the bottom of said printing depression. The cutter-slide is then 25 clamped in adjusted position. It is to be understood that whilst such adjustment is being made, the slide-bar 141 is in contact with its stops 151 for definitely limiting the downward movement of the cutting 30 edge.

The treadle is then released for raising the cutter out of the printing depression, and the cutter frame is adjusted laterally, by operation of the hand-wheel 138, and, if necessary, the carriage is moved by rotation 35 of the hand-wheel 86, to locate the cutting edge in a position at the unprinting portion of the mold which it is desired to provide with a bearer depression. The cutter-bar 40 92 is rotatively set by rotation of the handle 105 to present the cutting edge in desired direction for the direction of desired movement between the mold and the cutting edge. The cutter is then moved into the face side 45 of the mold by pressing on the treadle. The desired movement is then imparted either by the hand-wheel 86 for moving the carriage, or by the hand-wheel 138 for moving the cutter, as may be desired, or the direction 50 of presentation of the cutter may determine, or by both said hand-wheels if a diagonal path of the cutter is desired. The screw-rods 81 and 131 may have threads of comparatively high pitch for rapid traverse of 55 the cutter and carriage for rapid operation.

Assuming that a path is desired to form a parallelogram 175 in the printing portion of the mold, the cutting edge is presented in a direction transverse to the carriage and 60 the carriage moved rearwardly. The cutting edge is then rotated 90°, and the cutter-head moved laterally in one direction. The cutter-bar is then rotated another 90°, and the carriage moved forwardly the desired extent. The cutter-bar is then rotated an-

other 90°, and the cutter-head caused to travel in the opposite direction to complete the parallelogram.

If desired, the depth of cut may be obtained by successive settings and cuttings, 70 each removing a portion of the thickness of material for forming the depression, until the depression is of the desired depth.

It is desirable that the area of bearer depressions in the mold shall be gaged by the 75 density of the printing portions in the mold. Thus if the printing portions be close or dense, the bearer portions in the unprinting portions will be made dense, and if the printing portions be light, the bearer portions 80 in the unprinting portions will be made correspondingly light, to produce uniformity in thickness in the printing plate.

The action of the cutter is preferably to 85 remove the chips arising from the cutting past the upper surface of the mold, and the form of the cutter is preferably such that sharp outlines of the walls and bottom of the groove being cut are formed, and a sharp upper edge for said walls is provided. It 90 will be noted that the advancing side of the cutter is hollowed adjacent to its cutting edge, the body of the cutter receding as shown at 177 above the cutting edge, and then curving forwardly, as shown at 178, 95 for ready relief of the removed strip of the mold. The sides of the cutter adjacent to the cutting edge and throughout the walls of the groove formed by the cutter are sharp, for making clean cuts at the bottoms, 100 sides and upper edges of said walls.

Closely adjacent parallel grooves may also be cut in said unprinting portions of the mold, as well as grooves which merge into each other, and other forms and relations 105 of grooves may be cut, or any desired direction, width or shape of grooves or corelation of grooves may be cut, as may be desired.

The mold may be clamped on the carriage with its sides parallel with the sides of the 110 carriage, as shown in Fig. 17 or said mold may be clamped in any desirable angular position, depending on the directions in which it is desired to cut the grooves in the mold. These grooves are desirably cut 115 parallel with adjacent printing lines, so that, if the printing lines are angular with relation to the mold, the mold is desirably angularly clamped on the carriage.

When the printing plate is formed from 120 a mold formed as herein described, the after-formed bearer depressions are reproduced with the printing depressions in the printing plate as bearers and as printing elevations respectively, of equal height, for 125 forming a printing plate in which the printing portions which are weak in resistance to pressure or bending stresses, are strengthened by the bearers thus provided, for producing a printing plate in which the print- 130

ing portions are protected from injury by pressures applied to the printing plate, and in which all portions of the printing surface are uniformly bendable for providing 5 a curved printing plate properly curved throughout.

I do not herein claim the method of forming the mold for a printing plate, herein shown and described, having shown, described and claimed the same in a copending application filed by me in the United States Patent Office May 9, 1927, for patent 10 on improvements in method of forming molds for printing plates, as Serial No. 15 189,894.

What I do claim herein as my invention and desire to secure by Letters Patent, is:

1. In a bearer cutting machine for molds having indentations therein for the printing 20 portions of printing plates and areas of non-printing portions, the combination of a carriage provided with a supporting surface for the mold, a cutter having a cutting edge which is non-rotating during cutting and a 25 receding portion above said cutting edge for upward removal of the material cut, means for adjusting the angle of presentation of said cutting edge to the mold and maintaining said cutting edge in such ad- 30 justed angular positions, a slide for said cutter, a pivoted support for said slide, means for adjusting said slide on said sup- 35 port in a direction transverse to said sup- porting surface for positioning the cutting edge of said cutter in contact with the bottom of a printing indentation in said mold on said carriage, a stop for said sup- port during said last-named adjustment, treadle means for pivotally moving said 40 support and causing approach and recession between said cutting edge and said supporting face of said carriage, and means for

causing travel in relatively right angular directions in a plane parallel with said sup- 45 porting face between said support and said carriage, constructed and arranged for entry of said cutting edge into said areas of said non-printing portions and linear travel be- 50 tween said cutter and said carriage with said cutting edge in the plane of the bottoms of said depressions.

2. In a bearer cutting machine for molds having indentations therein for the printing portions of printing plates and areas of non- 55 printing portions, the combination of a frame, a carriage movable on said frame and provided with a supporting surface for a mold, a screw-rod extending transversely above said carriage, a cutter-support piv- 60 oted to and movable lengthwise of said screw-rod, a slide thereon, means for adjust- 65 ing said slide on said support, a cutter on said slide, said cutter having a cutting edge which is non-rotating during cutting, an operating bar, guiding means between said frame and said operating bar, limiting stops at the respective ends of said operating bar, 70 said operating bar having operative con- 75 nection with said pivoted support for piv- 80 otally moving said pivoted support, treadle means for operating said operating bar, means for rotating said screw-rod and thereby laterally moving said pivoted sup- port along said operating bar, means for causing travel of said carriage at right angles to said lateral movement of said sup- 85 port, and means for adjusting said cutter about its longitudinal axis for presentation of its cutting edge in different directions to the mold and maintaining said cutting edge in said adjusted positions while in the mold.

In testimony whereof, I have hereunto signed my name.

LESTER W. CLAYBOURN.
